Int. Cl. D12—99; D29—99
U.S. Cl. D48—32

FIG. 5

FIG. 6

FIG. 1 is a perspective view of a support bar showing my new design;

FIG. 2 is an enlarged side elevational view thereof, the opposite side being identical;

FIG. 3 is an enlarged top plan view thereof;

FIG. 4 is an enlarged fragmentary bottom perspective view thereof;

FIG. 5 is an enlarged front elevational view thereof;

FIG. 6 is an enlarged rear elevational view thereof;

FIG. 7 is a cross-sectional view taken on line 7-7 of FIG. 3;

FIG. 8 is a greatly enlarged sectional view of the top surface of the support bar indicated by the circle 8 in FIG. 7;

The lights, signal and vehicle are shown in broken lines in FIGS. 1, 2, and 5 for illustrative purposes only.

The support bar is broken away in FIGS. 3, 5 and 6 for convenience of illustration.

I claim:

The ornamental design for a support bar for vehicles, as shown and described.
